BODY ATTACHED WRITING ACCESSORY

Rundlette K. Palmer, Fredericksburg, Va.

Application September 12, 1956, Serial No. 609,490

5 Claims. (Cl. 120—8)

This invention relates to writing accessories and more particularly to a combined pen and pencil case having means for attaching the same to the body of the user and a retracting means for automatically retracting the pen and pencil within housings provided therefor when such pen or pencil is not in use. This invention is an improvement on that shown in my prior Patent #2,755,772, issued July 24, 1956 and on that shown in my prior application Serial No. 504,883, filed April 29, 1955, now Patent No. 2,793,617 issued May 28, 1957.

Heretofore, numerous types of pen or pencil holders incorporating retracting means have been proposed and utilized and some of these merely provided a retracting means for attachment to the apparel of the user and which served to retract the pen or pencil out of the way during periods of non-use thereof. Other of these prior art devices included means for containing or housing the pen or pencil during periods of non-use, but many of these were relatively heavy and cumbersome and frequently impeded normal movements of the hand of the user when the pen or pencil was in retracted position. These prior devices were likewise subject to frequent breakage or damage and they were of such construction that it was virtually impossible to repair or replace the retracting mechanism without completely dismantling the device and very often this operation rendered the device unfit for further use.

Devices of this nature have heretofore been somewhat objectionable due to the fact, that often they were not of pleasing appearance and were uncomfortable to wear and furthermore, in many instances, they were relatively costly thereby prohibiting sale of the same in a highly competitive market. These prior art devices in many cases failed to adequately protect the exposed point of the pen or pencil thereby permitting the same to soil or penetrate and damage the apparel of the user, which resulted in infrequent use of such devices after an initial trial thereof.

It is accordingly an object of the invention to provide a combined body attached pen and pencil case and retracting means which may be provided with a comfortable shape and pleasing appearance and which may be conveniently and economically manufactured from lightweight readily available materials and which may be conveniently applied to or removed from the wrist of the user.

A further object of the invention is the provision of a body attached pen and pencil case and retracting means in which there is also provided means for covering the pen and pencil when not in use thereby preventing damage or soiling of the garments of the user.

A still further object of the invention is the provision of a body attached pen and pencil case and retracting means in which such retracting means, as well as the pen and pencil may be conveniently removed and replaced from the rear ends of the housings provided therefor without requiring the use of special tools or operations

which might possibly render the device unfit for further use.

Another object of the invention is the provision of a body attached pen and pencil case and retracting means in which such retracting means comprises a unitary structure which may be conveniently packaged as an individual unit for use in replacing damaged or defective retracting units.

A further object of the invention is the provision of a combined body attached pen and pencil case and retracting means including a base of pliable material, such as leather or plastic which will provide a pleasing appearance and at the same time, conform to the wrist of the user thereby eliminating any discomfort.

15 A still further object of the invention is the provision of a combined body attached pen and pencil case and retracting means which may be conveniently attached to the wrist of the user thereby positioning the pen or pencil in a convenient location for removal and use in the fingers of the user and upon release of the same by the fingers of the user, such pen or pencil will be automatically retracted within the housings provided therefor and in which means is also provided to elevate the forward ends of the housings above the body, in order to maintain 20 the exposed tips of the pen and pencil spaced an appreciable distance from the hand of the user.

Another object of the invention is the provision of a combined body attached pen and pencil case and retracting means in which individual flaps are provided for 25 covering the retracting means, which flaps may be conveniently opened to permit removal and replacement of the retracting means upon failure or damage thereto.

A further object of the invention is the provision of 30 a combined body attached pen and pencil case and retracting means having a strap for securing the same to the wrist of the user and in which a flap fixed at one end to the strap and free at the other, extends between the wrist of the user and the body of the case in order to contribute to the comfort of wearing the same.

A still further object of the invention is the provision 35 of a combined body attached pen and pencil case and retracting means including tubular housings for receiving the pen and pencil when not in use and in which the forward ends of the housings are flared in order to facilitate entry of the pen and pencil thereto.

Further objects and advantages of the invention will be apparent from the following description taken in conjunction with the accompanying drawing wherein:

50 Fig. 1 is a top plan view of a body attached writing accessory including a pen and pencil case constructed in accordance with this invention;

Fig. 2 is a side elevational view of the writing accessory shown in Fig. 1;

55 Fig. 3 is a sectional view taken substantially on the line 3—3 of Fig. 1;

Fig. 4 a rear end elevational view of the writing accessory shown in Fig. 1; and

Fig. 5 a fragmentary sectional view showing the snap 60 means for retaining the flaps in position.

With continued reference to the drawing, there is shown a body attached writing accessory constructed in accordance with this invention and which may well comprise an elongated generally rectangular base 10 of pliable material, such as leather, plastic or any other suitable material. Secured to the upper surface of the base 10 are a pair of spaced substantially parallel elongated wedge members 11 and such wedge members extend longitudinally of the base 10 with the thick ends spaced inwardly from the forward end 12 of the base 10 and with the thin ends spaced inwardly from the rear end 13 of the base 10. A pair of elongated tubes 14 and 15 are

disposed on the wedge members 11 and the tubes 14 and 15 provide housings for a pen and pencil 16 and 17 respectively. The wall of each tube 14 and 15 is provided with a flared forward end 18 and 19 which serves to facilitate entry of the pen and pencil 16 and 17 during retraction thereof in a manner to be later described.

The tubes 14 and 15 are tapered and are somewhat larger in diameter at their rear ends than at the forward flared ends 18 and 19 and the rear ends of the tubes 14 and 15 terminate in longitudinally extending spring fingers 20 and 21 on the tube 14 and 22 and 23 on the tube 15. The tube 14 is provided with inwardly extending prongs 24 and 25 adjacent the juncture of the fingers 20 and 21 with the tube 14 and the tube 15 is provided with inwardly and rearwardly extending prongs 26 and 27 adjacent the juncture of the fingers 22 and 23 with the tube 15. A unitary retracting mechanism 28 is removably disposed between the spring fingers 20 and 21 and the retracting mechanism 30 is provided with a flexible element extending through a longitudinal aperture in a bumper 29 of yieldable material disposed in engagement with the prongs 24 and 25 and the flexible element is attached to the rear end of the pen 16. Similarly, a unitary retracting mechanism 30 is releasably positioned between the spring fingers 22 and 23 on the tube 15 and a flexible element extends through a longitudinal aperture in a yieldable bumper member 31 disposed in engagement with the prongs 26 and 27. The flexible member from the retracting mechanism 30 is secured to the rear end of the pencil 17 disposed in the tube 15. The bumper member 29 and 31 may be formed of yieldable material, such as leather or the like and such bumper members may be engaged by the rear ends of the pen and pencil 16 and 17, or by a loop or other fastening means 32 on the rear end of the pen and pencil 16 and 17 in order to cushion the same during retraction of the pen and pencil within the tubes 14 and 15. The retracting mechanisms 28 and 30 may be of the type shown and described in my prior Patent #2,755,772, issued July 24, 1956.

The tubes 14 and 15 may be held in place on the wedge members 11 by a hood 33 of suitable pliable material, which hood is disposed over the tubes 14 and 15 and may be secured to the base 10 by stitching, lacing or other suitable means 34 adjacent the side edges of the base 10 and by a line of stitching or lacing 35 between the tubes 14 and 15. Since the tubes 14 and 15 need not be removed from the device for repairs or servicing of the retracting mechanism and the like, the hood 33 may if desired, be permanently secured to the base 10 by any suitable means.

The hood 33 is provided at the rear end with an elongated slit 36 disposed midway between the tubes 14 and 15 and which slit 36 serves to provide flaps 37 and 38 for covering the retracting mechanisms 28 and 30. As best shown in Figs. 2 and 3, the flaps 37 and 38 extend over the retracting mechanisms 28 and 30 and downwardly to the rear thereof, there being provided snap means 39 on the flaps 37 and 38 and on the rear end of the base 10 in order to removably secure the flaps 37 and 38 in place. When it is desired to remove or replace the retracting mechanisms 28 and 30, as well as the pen and pencil 16 and 17, it is only necessary to release the snap means 39 thereby releasing the flaps 37 and 38, at which time the same may be folded back to expose the retracting mechanisms 28 and 30 which may be removed from between the spring fingers and thereafter the bumpers 29 and 31, as well as the pen and pencil 16 and 17 removed from the tubes 14 and 15. These elements may be replaced in the same manner and the flaps 37 and 38 moved to covering position and secured in place by engagement of the snap means 39. In this way, the retracting mechanism, as well as the pen and pencil may

be removed and replaced without removing the tubes 14 and 15 from the base 10.

The hood 33 is provided adjacent the forward end thereof, with strap means 40 for securing the device to the wrist of the user and the strap means 40 may well comprise one part 41 having a buckle 42 attached to the end thereof and another part 43 having eyelets 44 therein for receiving the tongue 45 of the buckle 42 in order to permit convenient adjustment of the strap means 40. The portion 43 of the strap means 40 may also be provided with a reinforcing and protective flap 46 which may be secured to the inner portion of the part 43 by the eyelets 44 or may be secured thereto in any other desired manner adjacent one end of the flap 46 and the opposite end 47 of the flap 46 extends beneath the body 10 and is free. Consequently, the flap 46 will be disposed between the wrist of the user and the body 10 and will thereby operate to smooth out any irregularities in the lower surface of the body 10 thereby providing a comfortable engagement with the wrist of the user.

The forward end 12 of the body 10 may be folded back upon itself, as best shown in Fig. 2, to provide pockets 48 for receiving the forward ends of the pen and pencil 16 and 17 and covering and manipulating flaps 49 and 50 may extend rearwardly from the pockets 48 in order to permit convenient engagement of the same with the forward ends of the pen and pencil 16 and 17 and in order to improve the flexibility of the forward end 12 of the body 10, there may be provided a triangular cutout 51 substantially midway between the pockets 48, which as best shown in Fig. 2, will permit the material of the forward portion of the body 10 to flex or yield during operation of the device.

As will be seen, the wedge members 11 elevate the forward ends of the tubes 14 and 15 above the body 10 and consequently, materially space the forward ends of the pen and pencil 16 and 17 from the back of the hand of the user and when it is desired to utilize either the pen or pencil 16 and 17, the same may be pulled forwardly from the tubes 14 and 15 by one hand of the user and grasped in the fingers of the hand of the user to which the device is attached. Upon completing the writing operation, it is merely necessary to release the pen or pencil 16 and 17 whereupon the retracting mechanism will pull the same rearwardly within the tubes 14 and 15, such movement being materially facilitated by the flared forward ends 18 and 19 of the tubes 14 and 15.

It will be apparent that the above described invention may be conveniently and economically manufactured in a variety of styles, materials and colors and that the same provides a convenient case for a pen and pencil without in any way impeding the use thereof and likewise, provides a means for automatically retracting such pen or pencil into the case after use thereof. There is, likewise, provided, as described above, a cover means for protecting the points of the pen and pencil to prevent soiling or damage of the apparel of the user and obviously, the invention may be conveniently worn on the arm inside the sleeve of the user and completely shielded from view. In addition, the structure permits removal and replacement of the retracting mechanism, as well as the pen or pencil without disassembly of the device and such operation is conveniently accomplished merely by opening a flap which serves to cover the retracting mechanism when in use.

It will be obvious to those skilled in the art that various changes may be made in the invention without departing from the spirit and scope thereof and therefore the invention is not limited by that which is shown in the drawing and described in the specification, but only as indicated in the appended claims.

What is claimed is:

1. A writing accessory of the character described comprising an elongated generally rectangular base of pliable

material, an elongated wedge member secured to the upper surface of said base longitudinally thereof, the thick end of said wedge member being spaced inwardly from the forward end of said base and the thin end of said wedge member being spaced inwardly from the rear end of said base, an elongated tube disposed on said wedge member with the forward end elevated above said base and providing a housing for a pen or pencil, a pen or pencil disposed in said housing, the wall of said tube adjacent the forward end being flared to facilitate entry of said pen or pencil, curved resilient fingers extending longitudinally from the rear end of said tube, inwardly extending prongs in the wall of said tube adjacent the juncture of said fingers with said tube, a bumper comprising a plug of yieldable material removably disposed in the rear end of said tube in engagement with said prongs and having an axially extending aperture, a unitary retracting mechanism removably retained between the fingers on said tube and including a flexible element extending through the aperture in said bumper and secured to the rear end of said pen or pencil whereby said pen or pencil, said bumper and said retracting mechanism may be removed and replaced from the rear end of said tube, a hood of pliable material disposed over said tube and attached to said base to secure said tube in place on said wedge member, a flap on the rear end of said hood for covering said retracting mechanism, snap means for releasably securing the rear end of said flap to said base, strap means extending from opposite sides of said hood adjacent the forward end for detachably securing said accessory to the wrist of the user, said strap means including a buckle on one part and eyelets in the other part, a wrist engaging flap secured adjacent one end to said other part and extending beneath said base with the opposite end free and a pocket in the forward end of said base for receiving the end of said pen or pencil disposed in said tube.

2. A writing accessory of the character described comprising an elongated generally rectangular base of pliable material, an elongated wedge member secured to the upper surface of said base longitudinally thereof, the thick end of said wedge member being spaced inwardly from the forward end of said base and the thin end of said wedge member being spaced inwardly from the rear end of said base, an elongated tube disposed on said wedge member with the forward end elevated above said base and providing a housing for a pen or pencil, a pen or pencil disposed in said housing, the wall of said tube adjacent the forward end being flared to facilitate entry of said pen or pencil, resilient fingers extending longitudinally from the rear end of said tube, inwardly extending prongs in the wall of said tube adjacent the juncture of said fingers with said tube, a bumper comprising a plug of yieldable material removably disposed in the rear end of said tube in engagement with said prongs and having an axially extending aperture, a unitary retracting mechanism removably retained between the fingers on said tube and including a flexible element extending through the aperture in said bumper and secured to the rear end of said pen or pencil whereby said pen or pencil, said bumper and said retracting mechanism may be removed and replaced from the rear end of said tube, a hood of pliable material disposed over said tube and attached to said base to secure said tube in place on said wedge member, a flap on the rear end of said hood for covering said retracting mechanism, means for releasably securing the rear end of said flap to said base and strap means extending from opposite sides of said hood adjacent the forward end for detachably securing said accessory to the wrist of the user, said strap means including a buckle on one part and eyelets in the other part.

3. A writing accessory of the character described comprising an elongated generally rectangular base of pliable material, an elongated wedge member secured to the

upper surface of said base longitudinally thereof, the thick end of said wedge member being spaced inwardly from the forward end of said base and the thin end of said wedge member being spaced inwardly from the rear end of said base, an elongated tube disposed on said wedge member with the forward end member elevated above said base and providing a housing for a pen or pencil, a pen or pencil disposed in said housing, the wall of said tube adjacent the forward end being flared to facilitate entry of said pen or pencil, resilient fingers extending longitudinally from the rear end of said tube, inwardly extending prongs in the wall of said tube, a bumper comprising a plug of yieldable material removably disposed in said tube in engagement with said prongs and having an axially extending aperture, a unitary retracting mechanism removably retained between the fingers on said tube and including a flexible element extending through the aperture in said bumper and secured to the rear end of said pen or pencil whereby said pen or pencil, said bumper and said retracting mechanism may be removed and replaced from the rear end of said tube, a hood of pliable material disposed over said tube and attached to said base to secure said tube in place on said wedge member, a flap on the rear end of said hood for covering said retracting mechanism, means for releasably securing the rear end of said flap to said base and means for detachably securing said accessory to the wrist of the user.

4. A writing accessory of the character described comprising an elongated generally rectangular base of pliable material, an elongated wedge member secured to the upper surface of said base longitudinally thereof, the thick end of said wedge member being disposed adjacent the forward end of said base and the thin end of said wedge member being disposed adjacent the rear end of said base, an elongated tube disposed on said wedge member with the forward end elevated above said base and providing a housing for a pen or pencil, a pen or pencil disposed in said housing, resilient fingers extending longitudinally from the rear end of said tube, inwardly extending prongs in the wall of said tube, a bumper comprising a plug of yieldable material removably disposed in said tube in engagement with said prongs and having an axially extending aperture, a unitary retracting mechanism removably retained between the fingers on said tube and including a flexible element extending through the aperture in said bumper and secured to the rear end of said pen or pencil whereby said pen or pencil, said bumper and said retracting mechanism may be removed and replaced from the rear end of said tube, a hood of pliable material disposed over said tube and attached to said base to secure said tube in place on said wedge member, a flap on the rear end of said hood for covering said retracting mechanism, means for releasably securing the rear end of said flap to said base and means for detachably securing said accessory to the wrist of the user.

5. A writing accessory of the character described comprising an elongated generally rectangular base of pliable material, an elongated wedge member secured to the upper surface of said base longitudinally thereof, the thick end of said wedge member being disposed adjacent the forward end of said base and the thin end of said wedge member being disposed adjacent the rear end of said base, an elongated tube disposed on said wedge member with the forward end elevated above said base and providing a housing for a pen or pencil, a pen or pencil disposed in said housing, resilient fingers extending longitudinally from the rear end of said tube, a unitary retracting mechanism removably retained between the fingers on said tube and including a flexible element secured to the rear end of said pen or pencil whereby said pen or pencil and said retracting mechanism may be removed and replaced from the rear end of said tube, a

hood of pliable material disposed over said tube and attached to said base to secure said tube in place on said wedge member, a flap on the rear end of said hood for covering said retracting mechanism, means for releasably securing the rear end of said flap to said base and means for detachably securing said accessory to the wrist of the user.
